RADIO RECEIVING SET

Juan Antonio Vila y Colombo, Habana, Cuba

Application August 8, 1932, Serial No. 627,979
In Cuba August 1, 1932

3 Claims. (Cl. 250—20)

This invention refers to radio receiving sets and has for its main object to provide certain improvements in the structure of devices of this kind, by which objectionable interference in radio reception is reduced and the quality and distinctness of the sound improved.

In the drawing:

- Figure 1 is a side elevation in detail of an arrangement including my invention.
10 Figure 2 is an end elevation in detail of same.
Figure 3 is a horizontal sectional view, in detail, according to line 3—3 of Figure 1.
15 Figure 4 is a cross vertical sectional view in detail, according to line 4—4 of Figure 1; and
Figure 5 is a perspective view of the arrangement.
20 By 1 is designated a metallic closed casing within which are secured uprights 2 provided on their inner faces with insulating plates 3. A coil 4 is wound on a copper core, which is supported in the plates 3, the terminals 6 and 7 of the coil passing through the bores 8 and 9 in the casing 1, and being connected to the binding post 14 in the antenna line of a radio receiving set.
25 Below the coil 4 there is arranged another coil 5 the core of which is made of iron or steel, and is secured in the insulating plates 3. The terminals 10 and 11 of the second coil pass through bores 16 and 17 and are connected to a binding 30 post 15 of the ground line of a radio receiving set.

The wire connecting the antenna to the lightning arrester must be of very small gauge, as well as those from the switch to the receiving set and also the wire to ground. The connection wire from the lightning arrester to the switch must be of larger gauge. 5

I claim:

1. In a radio receiving set, two closely arranged coils, cores supporting said coils and insulated from each other, one of said cores being formed of magnetizable material and the other being formed of copper, the coils being connected, respectively, with the antenna and ground leads. 10

2. In a radio receiving set, two closely arranged coils, cores supporting said coils and insulated from each other, one of said cores being formed of magnetizable material and the other being formed of copper, the coils being connected, respectively, with the antenna and ground leads, a casing enclosing the coils and cores, and insulating means supporting the cores in said casing. 15

3. In a radio receiving set, two closely arranged coils, cores supporting said coils and insulated from each other, one of said cores being formed of magnetizable material and the other being formed of copper, a casing enclosing the cores and coils, one of the coils being connected to the ground wire of the radio set and the other coil being connected with the antenna wire of the set. 25
